(54) **BRICK, MOULDING**

(76) Inventor: **Robert Rankin**

Robert Rankin.

The schedule referred to in the Letters Patent and
making part of the same, containing a description, in the
words of the said Robert Rankin himself, of his improve-
ment in the machine for moulding bricks.

To all whom it may concern, Be it known that I
Robert Rankin, in the County of Toledo and State
of Maine have invented certain improvements in
the machine for moulding bricks and that the
following is a full and exact description thereof:
A frame is made of such size and strength as may be
necessary, according to the power to be applied, in the
which I have constructed the foundation or ground sills
consist of a horizontal frame about six feet long, and
three feet eight inches wide. To this four vertical posts
are framed which rise to the height of eight feet; two of
these rise from one end of the side sills and the other
two at the distance of three feet eight inches from them
measured from out to out. These posts are enclosed
so as to form a box which is to contain the clay to be
mixed and moulded. The bottom of this box is two feet
above the ground, & its height four; the inside of it is
round and the moulding box has a vertical shaft
furnished with hives or cutters in its centre within it
comprizing hives or nodes, projecting from the inside
six or eight well known to those acquainted with the pre-
paring of clay for bricks, pottery, or other purposes.
The vertical shaft has a step in the bottom of the circular
box, and is supported at the top in the usual way, it
is to be turned by means of a sweep or lever by animal
power or other wise, & at the top of this shaft and just
below the sweep there is a wheel which turns a iron wheel
firmly fixed, and latter engaged with it. This wheel is

four feet, two inches in diameter and one foot thick, and upon it are formed an eccentric groove, inclined planes, & ears, by which motion is to be communicated to the moulding part of the machine. The prepared Clay passes through an opening left in the front side of this mixing well close to the bottom, into a box ^{or what so ever} I call the front of the machine. The following by which the moulding is effected rises and falls in this box which is of such length and width as may be necessary for moulding the bricks say for six bricks thirty inches long and one foot wide. The bottom of this box is divided by cross bars so as to form a kind of hopper or funnel to direct the Clay into the mould beneath it. The following is attached to the vertical shaft which is raised by the cam wheel. For this purpose it has near its periphery two inclining planes opposed to each other, upon the upper side of the wheel a friction roller runs, which roller turns on a pin projecting at right angles from the inner side of the bottom shaft. As the wheel turns this roller drives at the vertical side of the earthen which rises from the inclining planes and the following being caused the shaft falls by the bricks are moulded, the inclining planes then cause the following to rise by its action on the friction roller. The following is made double, the lower part which first comes in contact with the clay by the falling of the shaft strikes a blow upon its which materially aids the falling of the moulds and this part is attached to the upper one by sliding bolts which admit the second part which is heavily loaded to come down upon it and complete the pressure. The moulds are placed by hand upon a bed which forms the lower end of a vertical vibrating frame, the upper end of which is even with the upper ~~surface~~ of the cam wheel by which the vibration is effected.

For this purpose there is an executive groove made on the upper surface of the wheel, and one arm projects horizontally back from the upper end of the vibrating frame, having on it a friction roller which drops into the executive groove the latter being so formed as to throw the lower end with its moulded beaks twice out in every revolution between the periods of moulding. The vibrating frame is held in a groove which serves as a fulcrum at about one third of its length from the upper end. The end at its lower end which sustains the pressure rests upon two rails upon which it slides in and out. — Immediately after the moulding is effected a plate of metal as long as the mould slides over them and cuts off the superfluous clay acting thus far the part of a striking. This striking plate or cutter lies directly under the bottom of the moulding well and it is pushed forward, and drawn back, at the proper periods by means of cams or executive grooves on the lower part of the cam wheel. These act upon a lever vibrating on a fulcrum, the lower end of which lever is attached to the apparatus for cutting off the clay & drives it backward and forward. The cutter slides in a box or trough, having ledges which enable it to contain water a portion of which being constantly applied to the cutter causes it to perform its office smoothly and without clogging. It contains parts of the apparatus described may be arranged in a manner varying from that set forth, and the proportions of the various parts may be altered, whilst the principle of action remains substantially the same and I do not intend therefore to limit myself in these particulars. But I do claim as my own invention and for which I ask a patent is the executive motion on the cam wheel for vibrating the friction roller, as described, the double follower by which

re block is first struck upon the mortar, and heavy pressure afterwards made, — The blading, cutter with its appendages operating, in the manner described, and the general arrangement & combination of the respective parts, by which this machine differs in its character from all others previously used from the same purpose.
